JAMES B. EADS, OF ST. LOUIS, MISSOURI.

Letters Patent No. 105,056, dated July 5, 1870.

IMPROVEMENT IN PUMPS.

The Schedule referred to in these Letters Patent and making part of the same.

To all whom it may concern:

Be it known that I, JAMES B. EADS, of St. Louis, in the county of St. Louis and State of Missouri, have made certain new and useful Improvements in Sand and Soil-Pumps; and I do hereby declare the following to be a full and true description thereof, reference being had to the accompanying drawing and to the letters of reference marked thereon.

This invention relates to pumps for raising sand or other subsoil out of river beds or bottoms, for forming deep channels, or excavations for foundations of bridge-piers, or other purposes.

The nature of this improvement is in the arrangement of a rising pipe or tube, in which an upward current of water is created, of sufficient velocity to draw sand or soil into said pipe, and carry the same up in said pipe to be discharged at a proper point above.

To cause said upward current, I arrange a force-pipe, through which, by a suitable pump, water is forced to a head-piece at the lower end of the rising-pipe, said head-piece is properly formed to deflect the incoming fluid, to create the upward current, as required.

To enable those skilled in these arts to make and use my said device, I will now more fully describe the same, referring to the accompanying—

Figure 1 as an elevation; to

Figure 2 as a sectional elevation; and to

Figure 3 as a bottom plan, showing the arrangement and connection of the pipes and head-piece in one of the forms in which my said invention may be represented.

I form the head-piece of a body or housing, A, to which the force-pipe, B, connects by suitable joint and inlet-piece. The neck of the head-piece joins, by a screw or flange-joint, with the rising or discharge-pipe C at a. The lower end of the pipe C is flared out somewhat conically, following the form of the housing A, and there is formed between the end of the pipe C and the housing an annular chamber, D, into which the water enters from the force-pipe B.

At the bottom of the housing A, I arrange a nut or joint piece, E, having a proper connection with the housing, as shown at e, and within said joint-piece I secure the nozzle or inlet-pipe, F. The nozzle F extends up a suitable distance into the end, c, of the pipe C, and, as the upper surface of the joint-piece E forms the bottom of the chamber D, the fluid, as it

passes out of this chamber, is deflected to an upward current, around the nozzle F, and passes up into the discharge-pipe C. By the upward current thus produced a vacuum is formed, whereby the exterior fluid of the river, in which the head-piece is placed, is caused to enter the nozzle F, carrying with it sand or soil. The stuff thus raised is carried up the rising-pipe C, and may be discharged at any convenient point.

The head-piece A, and its connecting-pipes, are lowered, as the excavation is carried on, to keep the nozzle F in proper proximity to the subsoil of the water course.

The current of water in the force-pipe, B is made by a proper pump, giving a continual stream, the pump being located on a boat, barge, or platform above the water-level.

In order to regulate the velocity of the current in the rising-pipe C, in accordance with the weight and bulk of the sand or soil to be raised, the nozzle F connects by a screw-joint, f, with the joint-piece E, so that an operator may move the nozzle F up or down; then, owing to the conicality of the end c of the rising-pipe, the opening between the nozzle and the end c is made smaller or larger, to increase or diminish the velocity of the upward current in the discharge-pipe. The nozzle F may be turned by a proper wrench, engaging in notches on its lower edge. These notches are indicated in fig. 3.

A further regulation of the current velocity may be achieved by moving the joint-piece, to thus raise or lower the bottom of the chamber D, and decrease or increase the water-way under the bottom edge of ends c.

By the use of my said sand or soil-pump, a lift of any required height may be achieved, and the same is, therefore, applicable to the construction of deep excavations, where ordinary devices would be inefficient.

Having thus fully described my invention,
What I claim is—

The specific device shown and described, with flaring bottom and inclined sides, as described, for the purpose set forth.

JAS. B. EADS.
